UNITED STATES PATENT OFFICE.

JAMES D. SHOOTS, OF HORSEHEADS, NEW YORK.

NON-REFILLING BOTTLE.

SPECIFICATION forming part of Letters Patent No. 577,790, dated February 23, 1897.

Application filed March 13, 1896. Serial No. 583,002. (No model.)

To all whom it may concern:

Be it known that I, JAMES D. SHOOTS, a citizen of the United States, residing at Horseheads, in the county of Chemung and State of New York, have invented certain new and useful Improvements in Non-Refilling Bottles, of which the following is a specification.

My invention relates to a new and useful improvement in non-refilling bottles, and has for its object to provide such a device which after having been once filled and sealed and the contents drawn therefrom cannot again be filled without detection.

With these ends in view my invention consists in the details of construction and combination of elements hereinafter set forth, and then specifically designated by the claim.

In order that those skilled in the art to which this invention appertains may understand how to make and use the same, I will describe its construction and operation in detail, referring by letter to the accompanying drawings, forming a part of this specification, and in which—

Figure 1 is a side elevation of a bottle having my improvement applied thereto; Fig. 2, a central vertical section thereof, and Fig. 3, a plan view of the sealing-cap.

Heretofore considerable inconvenience and loss have been occasioned to a certain class of manufacturers and bottlers of liquids from the fact that after the original contents of a bottle have been used it has been refilled with an inferior liquid and used under the name of the original manufacturer with great detriment and financial loss to said manufacturer; but this difficulty I have entirely overcome by providing a seal which after the bottle has been filled the neck of the latter is forced into said seal, which has been previously supplied with a suitable cement, and thus secured so that its removal is impossible without its being first broken, effectually preventing the fraud which has heretofore taken place.

Referring to the drawings, A represents the bottle, and B the neck, which is provided with the large rounded flange G at its top and a smaller rounded one I just below, the two flanges being separated by the groove J,

in which the sealing material catches. After the bottle is filled it is closed, as usual, by the stopper C. Over the stopper is placed a glass cup-shaped seal D, having a depression E formed around its circumference for the purpose of facilitating its being sealed over the cork; and this is accomplished by partly filling the cup with any suitable material, such as plaster-of-paris, rock-cement, sulfur and sand, or fusible metal in a pliable state, and forcing the cap over the cork and mouth of the bottle and permitting the sealing material to set. When this has been accomplished, the depression formed in the cap will prevent its withdrawal, and the radial shape of the neck of the bottle will insure the sealing compound retaining a firm hold thereon. In practice the name of the manufacturer or bottler of the liquid is blown or otherwise formed upon the glass cap, or it may be printed upon the label and this pasted upon the inside of the cap, as clearly shown in Fig. 3, so as to be legible through the glass, and as the cork cannot be removed until the seal has been broken it will be obvious that when this has once been done it will be impossible to refill the bottle with an inferior liquid and represent it to be the original brand unless the seal be replaced, which will not be possible, as each manufacturer will have his own seal and label. This construction has a still further advantage in that the bottle is in no wise injured by the breaking of the seal, but can be returned and reused by the manufacturer by substituting a new seal for the one previously broken.

The particular sealing compound which is used to unite the seal of the bottle forms no part of my invention, as any suitable compound for this purpose may be used, the only requisite being that it shall, when set, be proof against alteration at temperatures under the melting-point of the cap.

Having thus fully described my invention, what I claim as new and useful is—

In a non-refillable bottle, the bottle provided with a neck B, having two flanges G, I, around its top edge, and the groove J, between the flanges, combined with a glass cap D having an inwardly-formed groove or crimp

100

E near its lower edge and which groove or crimp forms a corresponding flange or projection on the inner side of the cap to catch in the filling; and a filling of suitable material placed in the cap around the cork and upper end of the neck, substantially as shown.
5 In testimony whereof I have hereunto af-

fixed my signature in the presence of two subscribing witnesses.

JAMES D. SHOOTS.
